UNITED STATES PATENT OFFICE.

THOMAS ALLSOP, OF PHILADELPHIA, PENNSYLVANIA, ASSIGNOR TO THE PHILADELPHIA DRYING MACHINERY COMPANY, OF GERMANTOWN, PENNSYLVANIA, A CORPORATION OF PENNSYLVANIA.

DEVICE FOR SUPPORTING CHINAWARE OR THE LIKE DURING THE PROCESS OF MANUFACTURE.

Application filed January 23, 1920, Serial No. 353,437. Renewed April 8, 1925.

To all whom it may concern:

Be it known that I, THOMAS ALLSOP, a citizen of the United States, residing in Philadelphia, in the county of Philadelphia and State of Pennsylvania, have invented certain new and useful Improvements in Devices for Supporting Chinaware or the like During the Process of Manufacture, whereof the following is a specification, reference being had to the accompanying drawings.

The invention relates to trays for supporting articles such as china, porcelain, pottery, etc., during certain stages of their manufacture, more especially during drying after the application of the glazing solution,—at which time it is essential that they be supported in positions of best advantage for the draining of any excess coating. Because of differences of form, different articles dry best in different positions: for example, large plates or other similar comparatively shallow articles dry more readily when in a vertical position, while the drying of cups, saucers, bowls and so forth is expedited when they are laid flat. In order to meet the various requirements above noted, I have devised a tray which is capable of inversion upon suitable supports, and, when turned to one position, capable of sustaining its charges flat or horizontally, and when in the other, of sustaining them vertically.

The invention is also directed to devices for positively maintaining the tray against displacement upon its supports when in either of its positions.

The invention is further directed to means for keeping the tray in place or pivoting it during turning, for guiding it to seat properly on its supports, and for facilitating engagement of the means for preventing displacement of the tray, and which are further functional as guides in facilitating the interengagement of the devices above noted, after reversal.

The invention is also in part directed to a grilled tray of such form as to permit the ready flow of the drying medium therethrough, and which, upon removal from its supports, may be easily cleansed of any adhering dried particles of the glazing solution.

The invention further comprehends certain novel details of construction and ar-

angement which will be better understood from the detailed description which follows. 55

In the drawings, Fig. I, is a fragmentary plan view, showing a pair of conveyor sprocket chains between which is suspended a tray structure conveniently embodying my invention. 60

Fig. II, is an elevation of one end of the tray, showing to better advantage the manner of its suspension from the adjacent conveyor chain.

Fig. III, shows a cross section of the structure, taken as indicated by the line III—III in Figs. I and II; and 65

Fig. IV, is a sectional elevation of the tray, taken as indicated by the line IV—IV, in Fig. I. 70

The organization herein represented comprises a pair of conveyor chains 1, 1, having interposed in them at intervals, co-ordinated special links 2, 2, which serve as convenient means of support for the suspension of trays 75 of my improved construction, one of such trays being indicated by the numeral 3, in the drawings. These trays are hung from the chains 1, 1, by means of brackets 5, 5, between which they are spanned and by 80 which they are carried. These supporting brackets 5, 5 are freely fulcrumed at their tops about integral, inwardly projecting pivot lugs 6, 6 on the special chain links 2, 2, and are retained on said lugs by washers 85 7, 7, and cotter pins 8, 8. The brackets 5, 5, are provided with tray supporting means in the form of ledges 9, 9, which are pierced adjacent their ends with apertures 10, 10, preferably of quadrangular outline. These 90 apertures are adapted for co-operation with either one or the other of two pairs of correspondingly shaped studs 11, projecting from the upper and lower faces of U shaped or channel fittings 12, 12 that embrace the 95 side edges of the tray in the manner clearly shown in Fig. II. As will be seen from Fig. I, the fittings 12, 12, are centrally located along the sides of the tray and are secured by bolts 13, 13. By this arrangement of 100 correlative engagement means (such as 9 and 11) on tray and supports, the tray is positively held against substantial movement or displacement upon the mounting brackets or supports 5 in either of its positions through the instrumentality of the

105

studs 11, 11, the latter serving at the same time to prevent spreading of the brackets.

In order to prevent the complete detachment of the tray during turning, and also to

- 5 maintain it in a central position with respect to the suspension brackets, the fittings 12, 12, are formed with integral trunnions 15, 15, which project into vertical slots 16, 16, in the brackets. Thus it will be seen that as 10 the tray is turned from one position to another, the trunnions 15, 15, cooperate with the up and down guides at 16, 16 to keep the tray in place, and serve as fulcrum pivots,— and, by preserving the alignment of the 15 tray after reversal, facilitate the proper seating of the tray on the supports 5 and the engagement of the studs 11, 11, with the co-operating apertures 10, 10, in the supporting ledges 9, 9. If desired, however, the 20 tray may be bodily removed for cleaning by tilting the same to a sufficient angle to clear the chains and their appendages.

The tray 3 itself is a grilled structure comprising a series of spaced bars 20 united by 25 marginal strips 21, 21 extending across the bars above and beneath,—with interstices between the strips 21, 21 corresponding to the spacing of the bars 20. At one side (as shown, the lower) of the tray, the bars 20, 30 20 are all preferably supplemented or provided with cleats 22, of a triangular cross section, the ridges thus formed being capable of sustaining, with minimum contact area, articles laid flat or in horizontal position. Upon its other (upper) side, the tray bars are provided or supplemented with a 35 lesser number of similar cleats,—in the present instance, only two, symmetrically arranged as shown. By a series of upstanding spacing pins 25 in each, the cleats 23 are enabled to support shallower articles, such as plates, saucers, etc., in vertical positions as illustrated in Fig. II. The grilled construction of the tray (with the intersticed 40 formation of its side edges) permits the ready circulation of the drying medium when the tray is employed, for example, in pottery or china dryers, and thereby facilitates the ready diffusion of the drying medium about the supported charges, as a result of which, more uniform drying is accomplished. To facilitate circulation, the 45 fittings 12, 12, are so proportioned that, when attached to the tray, they afford passages 17 for the air across the ends of the bars 20 (Fig. II) that communicate with the interstices between the bars. Furthermore, the characteristic open construction of the tray facilitates drainage of any excess 50 glazing solution previously applied to the supported charges, and also cleaning of the trays after removal from the conveyor.

Although I have shown the tray or shelf 3 as employed in a chain type of conveyor, 55 it will be readily understood from the fore-

going description that the same may, with similar advantages, be used in conveyor trucks such as are ordinarily employed in connection with tunnel dryers.

Having thus described my invention, I 70 claim:

1. A structure of the character described, comprising a pair of mounting brackets with supporting ledges; a reversible tray spanned between the brackets and supported by said ledges; and means for preventing displacement of the tray when turned to either of its positions. 75

2. A structure of the character described, comprising a pair of supports; a reversible tray spanned between and carried by said supports; and correlative engagement means on tray and supports for preventing displacement of the tray when in either of its positions. 80

3. A structure of the character described, comprising a pair of mounting brackets with apertured ledges; a reversible tray spanned between the brackets and supported by said ledges; and projections on both faces of the tray adapted to engage with the apertures in the supporting ledges of the mounting brackets to prevent displacement of the tray when turned to either of its positions. 85

4. A structure of the character described, comprising a pair of supports, with up and down guides; a reversible tray spanned between and carried by said supports; and means at the ends of said tray co-operating with said guides to keep the tray in place 90 during reversal. 95

5. A structure of the character described, comprising a pair of vertically slotted mounting brackets with supporting ledges; a reversible tray spanned between said brackets adapted to be supported by said ledges in either of its positions; and trunnions projecting from the ends of the tray 100 engaged in the slots of the brackets. 105

6. A structure of the character described, comprising a pair of supports, with up and down guides; a reversible tray spanned between and carried by said supports; correlative engagement means on tray and supports for preventing displacement of the tray when in either of its positions; and means at the ends of said tray co-operating with said guides to keep the tray in place 110 during reversal, and to facilitate interengagement of the correlative engagement means aforesaid after reversal. 115

7. A structure of the character described, comprising a pair of vertically slotted mounting brackets with apertured ledges; a reversible tray adapted to be supported by said brackets in either of its positions; fittings embracing the edges of the tray having on their upper and lower faces studs for co-operating with corresponding apertures in the bracket ledges to prevent dis- 120

placement of the tray when in either of its positions, said fittings also having trunnions for engagement in the bracket slots.

8. A structure of the character described, comprising a pair of spaced conveyor chains; co-ordinated mounting brackets pivotally suspended from said chains; reversible trays supported by said brackets; and means for preventing displacement of the trays when turned to either of their positions upon said brackets.

9. A grilled tray comprising a plurality of spaced bars secured together with interstices between them at their ends, and channel fittings embracing the ends of said bars affording across them passages communicating with said interstices.

10. A grilled tray comprising a number of spaced bars supplemented at top and bottom with cleats of triangular cross section; and spacing pins projecting from certain cleats upon one face of the tray, substantially as described and for the purpose set forth.

25 11. In an apparatus of the character described, a reversible tray adapted to support the articles to be dried in either of its positions.

12. In an apparatus of the character described, a reversible tray adapted to support the articles to be dried in either of its positions, said tray being provided with means for supporting said articles on edge.

30 13. In an apparatus of the character described, a reversible, apertured tray adapted to support the articles to be dried in either of its positions, said tray being provided with means for supporting said articles on edge.

35 14. In an apparatus of the character described, a reversible tray for supporting the articles to be dried, said tray being provided

with means for supporting said articles on edge.

15. In an apparatus of the character described, a reversible tray for supporting the articles to be dried, said tray being provided with pins for supporting said articles on edge.

16. In an apparatus of the character described, an apertured reversible tray for supporting the articles to be dried, said tray being provided with means for supporting the articles on edge.

17. In an apparatus of the character described, an apertured reversible tray for supporting the articles to be dried, said tray being provided with pins for supporting the articles on edge.

18. In an apparatus of the character described, a tray for supporting the articles to be dried, said tray being provided with slots V-shaped in their upper part.

19. In an apparatus of the character described, a tray for supporting articles to be dried, said tray being provided with slots V-shaped in their upper part, and rectangular in their lower part.

20. A structure of the character described, comprising a pair of supports, and a reversible tray, adapted to support the articles to be dried in either of its positions, spanned between and carried by said supports.

21. A structure of the character described, comprising a pair of supports, and a reversible tray pivotally and slidably attached to said supports.

In testimony whereof, I have hereunto signed my name at Philadelphia, Pennsylvania, this 20th day of January, 1920.

THOMAS ALLSOP.
